UNITED STATES PATENT OFFICE

155,291

DESIGN FOR A COMBINED TOBACCO POUCH
AND LIGHTER

Robert F. Kirby, North Attleboro, Mass., assignor to Evans Case Co., a corporation of Massachusetts

Application May 7, 1949, Serial No. 2,520

Term of patent 14 years

(Cl. D48—27)

To all whom it may concern:

Be it known that I, Robert F. Kirby, a citizen of the United States of America, residing at North Attleboro, county of Bristol, State of Massachusetts, have invented a new, original, and ornamental Design for a Combined Tobacco Pouch and Lighter, of which the following is a specification, reference being had to the accompanying drawing, forming a part thereof.

I claim:

The ornamental design for a combined tobacco pouch and lighter, substantially as shown and described.

ROBERT F. KIRBY.
